DESIGN FOR A BURIAL CASKET FOR PET ANIMALS OR SIMILAR ARTICLE

John S. Newlon, Nevada, Mo.

Application December 9, 1943, Serial No. 111,959

Term of patent 14 years

(Cl. D19—1)

To all whom it may concern:

Be it known that I, John S. Newlon, a citizen of the United States, residing at Nevada, in the county of Vernon and State of Missouri, have invented a new, original, and ornamental Design for a Burial Casket for Pet Animals or Similar Article, of which the following is a specification, reference being had to the accompanying drawing, forming part thereof.

Figure 1 is a top plan view of a burial casket for pet animals showing my new design, Figure 2 is an end elevational view, and Figure 3 is a side elevational view.

I claim:

The ornamental design for a burial casket for pet animals or similar article, as shown.

JOHN S. NEWLON.
